MECHANISM FOR FINISHING STEREOTYPE PLATES

Charles Alonzo Harless, Oak Park, Ill., assignor to The Goss Printing Press Company, Chicago, Ill., a corporation of Illinois

Application September 20, 1934, Serial No. 744,762

23 Claims. (Cl. 90—26)

The invention relates to a new and useful machine for producing stereotype printing plates and comprises mechanism for broaching the interior projections or ribs of the plate to the size and true cylindrical form of the plate cylinder of the press.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a top plan view of a machine embodying the invention;

Fig. 2 is a longitudinal vertical section taken on the line 2—2 of Fig. 1, showing the broach at the end of its working stroke and the plate-holding fixture open, and the saddle engaging the plate for removal;

Fig. 3 is similar to Fig. 2, but showing the broach at the return to the initial position, and the guide bar retracted beyond the plate-holding fixture;

Fig. 4 is a detached detail, with parts in section, and parts broken away, of the plate-containing saddle;

Fig. 5 is a top plan of Fig. 4;

Fig. 6 is an enlarged transverse vertical section on the line 6—6 of Fig. 1, looking in the direction of the arrows;

Fig. 7 is a vertical transverse section, on the line 7—7 of Fig. 1, looking in the direction of the arrows;

Fig. 8 is an elevation of Fig. 1 looking from the right-hand side of the sheet, substantially from the line 7—7 to the right-hand end; and

Fig. 9 is an enlarged detail vertical section taken on the line 9—9 of Fig. 1, looking in the direction of the arrows.

The invention provides a machine for producing, that is, casting and finishing cylindrical stereotype plates having inner projections or ribs extending longitudinally, that is, parallel to the axis of the plate, and constituting the seat or support for the plate upon the plate cylinder of the press. These longitudinal ribs or projections

are also preferably disposed radially, and the plate is removed longitudinally from the core of the casting machine. The machine is well adapted for the production of cylindrical plates, including both semi-cylindrical plates as well as 5 tubular plates, that is, plates which extend more than a semi-circumference about the plate cylinder of the press, and in many cases extend through 300 or more degrees of arc. To facilitate the removal of such plates from the 10 core of the casting box, the inner, longitudinally-disposed projections or ribs are beveled or tapered longitudinally from one end thereof to the other, and also preferably from the roots to the crowns or faces of the respective ribs. 15 The machine is equally well adapted for the production of plates having plate locking lugs on the interior which are engaged by devices on the plate cylinder to draw the plate about the cylinder. A plate of this kind is shown and described 20 in copending application Ser. No. 736,816 of Frank A. Foster, filed July 25, 1934. In this kind of plate the locking lugs also are preferably beveled longitudinally to facilitate the longitudinal withdrawal of the plate from the casting box 25 core.

In the finished operation in accordance with my machine, the unfinished stereotype plate is held resiliently, that is, the printing surface of the plate is brought to and held in true cylindrical 30 form, by pressing the plate slightly, or in other suitable manner, and a cylindrical broach of the same radius as the plate cylinder of the printing press, moving coaxially with the held stereotype plate, finishes the inner surface of the ribs, and 35 of the locking lugs when employed, to the shape and the radius of the plate cylinder of the press.

In the casting of the plates, a core is used having longitudinally disposed grooves or recesses of slightly decreasing cross-section from one end 40 thereof to the other, whereby the ribs, and locking lugs when used, are correspondingly tapered to facilitate the longitudinal withdrawal of the plate from the core. The present preferred embodiment of plate finishing means comprises 45 broadly a plate-holding fixture into which the unfinished plate may be readily inserted and from which the finished plate is readily withdrawn, the fixture bringing the printing surface of the plate resiliently into true cylindrical form. A 50 multiple cylindrical broach traveling coaxially with the printing surface of the plate, by successive cuts on a single travel of the multiple broach, finishes the interior surface or surfaces of the plate on a true cylinder coaxial with the printing 55

surface of the plate and on the radius of the printing cylinder of the press. The plate is preferably automatically removed from the fixture coincident with the return of the broach after its working movement.

In this exemplary preferred embodiment there is provided an openable and closable cylindrical plate-holding fixture, and when open a tubular plate may be readily placed directly therein and the finished plate removed therefrom in like manner, the closing of the fixture slightly compressing the plate with its printing surface against a true cylindrical surface and then holding it against longitudinal movement; a cylindrical multiple broach of the radius of the press cylinder is guided and hydraulically driven coaxially with the plate to finish the interior of the ribs to the exact shape and radius of the plate cylinder of the press on a single travel of the broach; and mechanism for automatically removing the finished plate from the opened fixture and returning the mechanism to the initial point of its cycle.

It will be understood that the foregoing general description, and the following detailed description as well, are illustrative and exemplary but are not restrictive of the invention.

Referring now in detail to the embodiment of the invention illustrated by way of example in the accompanying drawings, the mechanism is mounted on a suitable frame 1, and supported upon the frame is a stereotype plate-holding fixture 2, capacitated to resiliently hold a tubular stereotype plate with its printing surface in true cylindrical form and of the proper diameter for printing in the press, and to hold it also against displacement either angularly or axially, preparatory to drawing through the interior a cylindrical and concentric broach of the exact dimension of the plate-holding cylinder of the press. The plate-holding fixture 2 is openable to receive the unfinished stereotype plate and to deliver the finished plate, and as embodied, the upper half 5 of the fixture 2 is hinged at 6 and 7 on a rod 8, carried by the lower and fixed half 4 of the fixture. Suitable means 14 for locking the upper part 5 in closed position are provided. Each of said locking devices 14 (see Figs. 1 and 7) comprises a cam 15, mounted on a lever 16 which is pivotally mounted on a link 18 pivoted at 17 on one member of the plate fixture or housing. When the lever is moved to the position of Fig. 7 the cam draws the two halves of the fixture powerfully together with the plate within. To prevent end-wise or axial displacement of the stereotype plate A, arcuate stops 9 and 10 are fixed to the forward ends of the two halves of the fixture. Suitable stops, preferably a plurality of rollers 11, are mounted in the lower fixed half 4 of the fixture, against which the straight edges of the stereotype plate rest to angularly position the plate in the fixture before it is closed and to hold it against angular displacement. Thus the plate will be held in position within the closed fixture with its printing face resiliently pressed against a smooth inner surface of such character as will not injure the printing surface of the plate, and representing the printing radius of the plate on the press.

In the illustrative embodiment the broach is operated hydraulically, and as shown a multiple cylindrical broach 21 is mounted freely on a cylindrical guide bar 22, which bar is longitudinally slideable in a forward bearing block 23 and a rear bearing block 24 fixed on the machine frame. The guide rod 22 is attached to and detachable

from a yoke which is driven by the hydraulic cylinders. For this purpose, rod 22 is slotted at its forward end to receive a rearwardly-projecting tongue 27, which is fixed to a bolt 28, which passes through the central portion of a transverse yoke 29 and is fastened in position by a nut 30. The yoke 29 is connected to the hydraulic cylinders by the forward ends of piston rods 31 and 32 of hydraulic cylinders 33 and 34, passing through openings in the ends of the yoke, nuts 39 being threaded onto the ends of rods 31 and 32. The hydraulic cylinders 33 and 34 are horizontally disposed and extend longitudinally at either side of the machine frame, the cylinder 33 being supported at its ends by frame members 35 and 36, and cylinder 34 being mounted on similar frame members 37 and 38. The cylinders drive the mechanism through a double stroke to draw the broach from its initial position through the stereotype plate and after removal of the plate to restore it to initial position for the next succeeding reciprocation, the two extreme positions of the broach being shown in Figs. 1 and 2.

In the present embodiment, the guide rod 22 is detached from the yoke when in the position of Fig. 1, and the guide rod is retracted to the left from the position shown in Fig. 1 to that shown in Fig. 3, that is, until its front end is clear of the plate-holding fixture, to permit insertion of a new tubular stereotype plate in the fixture, and the guide rod is then returned, to the right in Fig. 1, and fixed to the yoke 29 preparatory to broaching the new plate. In the embodied form of means for detaching, retracting and returning the guide rod, a key 49 passes through the forward slotted end of guide rod 22 and through the tongue 27 of the yoke 29 to fix them together, and to release the guide rod from the yoke. As embodied, the guide rod is retracted and returned by manually operated devices. On the under side of the guide rod and extending longitudinally thereof is a gear rack 51, and mounted in the guide bearing 24 is a gear wheel 52, with its shaft 53 journaled in the bearing. Meshing with gear wheel 52 is a pinion 55, fixed on a shaft 50, which is journaled in the machine frame. A crank 56 is fixed to shaft 50.

To connect and disconnect the broach and guide rod, just back of the broach an annular groove is formed in the guide rod in which sets a U-shaped collar 59, which may be dropped into and lifted out of the groove. At the end of the cycle of movement of the broach, when the mechanism is in the position shown in Fig. 1, the key 49 is lifted out, thereby disconnecting the guide rod 22 from the yoke 29. Crank 56 is used to rotate gear 52, and after collar 59 is removed, the guide rod is retracted from the position of Fig. 1 to that of Fig. 3, thereby leaving the plate-holding fixture free, and a new plate to be finished is inserted in the open fixture, and the lid is closed. Crank 56 is then rotated in the opposite direction, and guide rod 22 is moved from the position of Fig. 3 to that of Fig. 1, key 49 is dropped into place, connecting guide rod 22 and yoke 29, collar 59 is dropped behind the broach, as shown in Fig. 1, and the mechanism is ready for the next broaching operation.

The embodied form of plate-removing means for delivering the finished plate from the fixture ahead of the returning broach (Figs. 1 and 3 to 6) comprises a saddle-plate 66, mounted in a horizontally-disposed slot 67 formed in the upper face of guide rod 22, there being a corresponding aligned slot 68 in the upper part of the bear-

ing block 24. The plate saddle 66 is resiliently mounted in a suitable manner as, for instance, by resting upon springs 69 and 70 nested in the guide rod 22, and the saddle has at its forward end a plate-engaging hook 71. At the end of the broaching stroke, the saddle is in the position shown in Fig. 2, and the hook 71, due to its spring action, has engaged the forward end of a finished plate A. On the return stroke of the 10 hydraulic cylinders, the fixture 2 is open, and the plate A, mounted on saddle 66, is carried to the left ahead of the returning broach to the position shown in Fig. 1, and the finished plate is then removed endwise from the saddle and over 15 to the rear end of the guide rod 22.

The embodied control mechanism for the hydraulic cylinders (Figs. 2, 7 and 8) is operated both manually and automatically, the power being turned on by the attendant and being shut 20 off automatically at the close of the stroke. The supply of pressure fluid to the cylinders 33 and 34 is controlled by a reversible valve 79. The stem 80 of this valve extends outwardly and fixed thereto is a control lever 81, operated both 25 manually and by the mechanism, as already mentioned. Fixed to the yoke 29 (Figs. 7 and 8) and extending along the machine frame is a rod 84, which moves to and fro longitudinally with the yoke. Fixed on the rod 84 are two stops 83 30 and 93, and astride rod 84, in the path of the stops, is a forked lever 87. Lever 87 is pivoted on the frame at 88, and at its lower end it is pivotally connected to a rod 89, which rod is pivoted at its other end 90 to the lever 81. The 35 power is turned on for the forward stroke by manually moving the lever 81 to the right, and at the end of the stroke the stop 83 engages and rocks lever 87 to the right, thereby restoring lever 81 to the neutral position, cutting off the power and stopping the mechanism. For the 40 return stroke, lever 81 is rocked manually to the left to turn on the power, and at the end of the stroke stop 93 engages lever 87, rocking it to the left and thereby moving lever 81 back to neutral 45 position and cutting off the power.

The invention in its broader aspects is not limited to the specific mechanisms shown and described but departures may be made therefrom within the scope of the accompanying 50 claims without departing from the principles of the invention and without sacrificing its chief advantages.

What I claim is:

1. A machine for finishing cylindrical stereotype plates including in combination, means for resiliently holding a stereotype plate with its printing surface in true cylindrical form, a cylindrical broach of the same radius as the printing cylinder of a press and means including a 55 longitudinally reciprocable bar on which the broach is mounted for effecting relative movement of the plate and broach on their common axis to finish the interior of the plate to the same true cylindrical form as the press cylinder 60 and means preventing rotary movement of said bar.

2. A stereotype plate finishing machine including in combination a multi-part fixture 65 openable to receive a plate and closable to hold the plate with its printing surface in true cylindrical form, a concentric cylindrical broach, means for moving the broach axially to finish the interior of the plate and for reversely returning the broach to its original position, and means 70 for removing the finished plate from the open

fixture prior to the return movement of the broach.

3. A stereotype plate finishing machine including in combination a multi-part, hinged fixture 5 openable to receive a plate and closable to hold the plate with its printing surface in true cylindrical form, a concentric cylindrical broach, a guide for the broach extending through the fixture, means for moving the guided broach to finish the interior of the plate, and means for 10 removing the finished plate from the open fixture.

4. A stereotype plate finishing machine including in combination a fixture for holding a plate with its printing surface in true cylindrical 15 form, a concentric cylindrical broach, a guide for the broach extending through the fixture, means for moving the guided broach axially to finish the interior of the plate, and means for 20 removing the guide from the fixture preparatory to the insertion of an unfinished plate.

5. A stereotype plate finishing machine including in combination a fixture for holding a plate with its printing surface in true cylindrical 25 form, a concentric cylindrical broach, a guide for the broach extending through the fixture, means for moving the guided broach axially to finish the interior of the plate and for reversely returning the broach to its original position, and means 30 for removing the guide from the fixture preparatory to the insertion of an unfinished plate.

6. A stereotype plate finishing machine including in combination a fixture for holding a plate with its printing surface in true cylindrical form, 35 a concentric cylindrical broach, a guide for the broach extending through the fixture, means for moving the guided broach axially to finish the interior of the plate and for reversely returning the broach to its original position, means for 40 removing the finished plate, and means for removing the guide from the fixture preparatory to the insertion of an unfinished plate.

7. A stereotype plate finishing machine including in combination a fixture for holding a plate with its printing surface in true cylindrical form, 45 a concentric cylindrical broach, means for moving the broach axially to finish the interior of the plate, said means including a guide bar on which the broach is mounted and a guide for said bar within which the bar reciprocates.

8. A stereotype plate finishing machine including in combination a fixture for holding a plate with its printing surface in true cylindrical form, 55 a concentric cylindrical broach, means for moving the broach axially to finish the interior of the plate, said means including a longitudinally moving guide bar on which the broach is mounted, and means for guiding the bar within which the bar reciprocates.

9. A stereotype plate finishing machine including in combination a fixture for holding a plate with its printing surface in true cylindrical form, 60 a concentric cylindrical broach, means for moving the broach axially to finish the interior of the plate, said means including a guide bar on which the broach is mounted, and means mounted on said guide bar for removing the finished plate.

10. A stereotype plate finishing machine including in combination a fixture for holding a plate with its printing surface in true cylindrical 70 form, a concentric cylindrical broach, and means for moving the broach axially to finish the interior of the plate and for reversely returning the broach to its original position, said means including a longitudinally reciprocable guide bar on 75

which the broach is mounted and means for preventing rotational movement of the bar.

11. A stereotype plate finishing machine including in combination a fixture for holding a plate with its printing surface in true cylindrical form, a concentric cylindrical broach, means for moving the broach axially to finish the interior of the plate and for reversely returning the broach to its original position, said means including a longitudinally reciprocable guide bar extending within the fixture and on which the broach is mounted, and means for removing said guide bar from the fixture for the insertion of an unfinished plate.
12. A stereotype plate finishing machine including in combination a fixture for holding a printing plate with its printing surface in true cylindrical form, a concentric cylindrical broach, means for moving the broach axially to finish the interior of the plate and for reversely returning the broach to its original position, said means including a reciprocable guide bar extending within the fixture and on which the broach is mounted, and means for moving said guide bar longitudinally to clear the fixture for the insertion of an unfinished plate.
13. A stereotype plate finishing machine including in combination a fixture for holding a plate with its printing surface in true cylindrical form, a concentric cylindrical broach, means for moving the broach axially to finish the interior of the plate, said means including a guide bar on which the broach is mounted, and means for moving the guide bar and broach longitudinally together through the fixture to finish the plate.
14. A stereotype plate finishing machine including in combination a fixture for holding a plate with its printing surface in true cylindrical form, a concentric cylindrical broach, means for moving the broach axially to finish the interior of the plate, said means including a guide bar on which the broach is mounted, and means for moving the guide bar and broach longitudinally together through the fixture to finish the plate and in the reverse direction to return the broach to original position.
15. A stereotype plate finishing machine including in combination a fixture for holding a plate with its printing surface in true cylindrical form, a concentric cylindrical broach, means for moving the broach axially to finish the interior of the plate, said means including a guide bar on which the broach is mounted, and means for moving the guide bar and broach through the fixture to finish the plate, and means for moving the guide bar clear of the fixture preparatory to inserting an unfinished plate in the fixture.
16. A machine for finishing curved stereotype plates including in combination a plate holding fixture having two cylindrical members openable to receive a plate and closable to hold the plate resiliently pressed to true cylindrical form, cylindrical cutting means for trimming the interior of the plate, and means for moving the cutter to and fro axially of the plate, said means including a hydraulic cylinder driving the cutter on its trimming stroke.
17. A machine for finishing curved stereotype plates including in combination a plate holding fixture having two cylindrical members openable to receive a plate and closable to hold the plate resiliently pressed to true cylindrical form, cylindrical cutting means for trimming the interior of the plate, a bar carrying and guiding said cutting means, and a hydraulic cylinder

driving the bar and cutter on the trimming stroke.

18. A machine for finishing curved stereotype plates including in combination a plate holding fixture having two cylindrical members openable to receive a plate and closable to hold the plate resiliently pressed to true cylindrical form, cylindrical cutting means for trimming the interior of the plate, a bar movable coaxially with said fixture and carrying said cutting means, a hydraulic cylinder driving the bar and cutter on the trimming stroke, and means for moving said bar backwardly preparatory to trimming a succeeding plate.

19. A machine for finishing curved stereotype plates including in combination a plate holding fixture having two cylindrical members openable to receive a plate and closable to hold the plate resiliently pressed to true cylindrical form, cylindrical cutting means for trimming the interior of the plate, a bar movable coaxially with said fixture and carrying said cutting means, a hydraulic cylinder driving the bar and cutter on the trimming stroke and manually operable means for moving said bar backwardly preparatory to trimming a succeeding plate.

20. A machine for finishing curved stereotype plates including in combination a plate holding fixture having two cylindrical members openable to receive a plate and closable to hold the plate resiliently pressed to true cylindrical form, cylindrical cutting means for trimming the interior of the plate, a member reciprocable coaxially with said fixture and carrying said cutting means, means for moving said member and cutter to and fro coaxially within said fixture including a hydraulic cylinder driving the cutter on the cutting stroke and manually operable means for retracting said member.

21. A machine for finishing curved stereotype plates including in combination a plate-holding fixture having two cylindrical members openable to receive the plate and closable about the plate, means including a cam and operating lever for pressing the closed members together, cylindrical cutting means for trimming the interior of the plate, and means for moving the cutter to and fro axially of the plate, said means including a hydraulic cylinder driving the cutter on its trimming stroke.

22. A machine for finishing curved stereotype plates including in combination a plate-holding fixture having two cylindrical members openable to receive a plate and closable to hold the plate resiliently pressed to true cylindrical form, cylindrical cutting means for trimming the interior of the plate, means for moving the cutter to and fro axially of the plate, said means including a hydraulic cylinder driving the cutter on its trimming stroke, and means operating automatically on the completion of the cutting stroke for cutting off the forward drive of the hydraulic power.

23. A machine for finishing curved stereotype plates including in combination a plate-holding fixture having two cylindrical members openable to receive a plate and closable to hold the plate resiliently pressed to true cylindrical form, cylindrical cutting means for trimming the interior of the plate, means including a hydraulic cylinder for driving the cutter on its trimming and return stroke, and means operating automatically on the completion of the return stroke for cutting off the hydraulic power.
